UNITED STATES PATENT OFFICE.

MICHAEL FITZGERALD, OF MEDINA, NEW YORK.

STREET OR STATION INDICATOR.

1,217,737.

Specification of Letters Patent. Patented Feb. 27, 1917.

Application filed March 3, 1916. Serial No. 81,940.

To all whom it may concern:

Be it known that I, MICHAEL FITZGERALD, a citizen of the United States, residing at Medina, in the county of Orleans and State 5 of New York, have invented new and useful Improvements in Street or Station Indicators, of which the following is a specification.

This invention relates to certain novel 10 and useful improvements in street or station indicators.

In carrying out the present invention, it is my purpose to provide a device of the class described which will be found especially 15 useful on street cars, interurban cars, etc., and which may be operated by the conductor of the car to indicate the names of the streets or stations successively as the car approaches such streets or stations, which will 20 embody comparatively few parts and these so correlated and arranged as to reduce the possibility of derangement to a minimum, which may be manufactured and installed at small cost, and which will operate efficiently and effectively for its intended purpose.

With the above and other objects in view, the invention consists in the construction, combination and arrangement of parts here- 30 after set forth in and falling within the scope of the claims.

In the accompanying drawings:

Figure 1 is a front elevation of a street or station indicator constructed in accordance 35 with the present invention.

Fig. 2 is a side elevation thereof.

Fig. 3 is a similar view of the opposite side.

Fig. 4 is a vertical sectional view there- 40 through.

Fig. 5 is a fragmentary vertical enlarged sectional view showing one of the shafts and the brake associated therewith.

Referring now to the drawings in detail, 45 1 designates a substantially rectangular casing having the front wall formed at a point approximately centrally of its height, with a transverse sight opening 2. Secured to the top and bottom walls of the casing 1 are 50 brackets 3 of suitable construction whereby the casing may be fastened to an appropriate part of the car.

Arranged across the casing 1 and journaled in bearing openings formed in the side 55 walls thereof are horizontal shafts 4 and 5 arranged one above the other and fixed upon

each shaft within the casing is a drum 6. Arranged across the casing 1 immediately behind the front wall thereof adjacent to the top and bottom walls of the sight opening 2 are cross bars 7 and secured to and wrapped about the respective drums 6 are the ends of a web 8 having the intermediate portion thereof trained over the bars 7 and movable across the sight opening 2 and 65 printed upon the web 8 and appropriately spaced apart are the names of the streets or stations to be indicated.

The ends of the shafts 4 and 5 project beyond the side walls of the casing and fixed 70 upon the ends of the shafts at one side of the casing are ratchet wheels 9, while loosely mounted upon said ends of the shafts are the limbs of yokes 10 and the stems of the 75 yokes project toward each other and overlap. Formed in the overlapping ends of the stems of the yokes 10 are elongated slots 11 through which is passed a pin 12 and connected to the ends of the pin 12 is a yoke 13. One end of the pin 12 projects beyond the 80 yoke and is disposed in a horizontal guide 14 secured to the adjacent side wall of the casing, while connected to the yoke 13 is a pull cord 15. Secured to the shaft ends of the yokes 13 and projecting outwardly therefrom are arms 16 and connected to the arms 85 16 are the corresponding ends of springs 17, the other ends of the springs being secured to brackets 18 fastened to the casing. Pivoted within each yoke 13 is a spring actuated dog 19 normally held in engagement with the teeth of the ratchet wheel, while formed on each dog 19 and projecting outwardly therefrom is a pin 20. Pivoted upon the outer member of each yoke is a releasing 90 arm 21 having the outer end thereof rounded as at 22 and formed centrally with a depression 23. These arms 21 are adapted to move into engagement with the respective pins 20 95 so as to swing the dogs out of engagement with the ratchet wheels and when the pins drop into the depressions 23, the dogs are held against return to normal position against the action of their springs.

The springs 17 act to hold the overlapping ends of the stems of the yokes normally at the rear end of the casing and disposed in the path of movement of the stems of the yokes are buffers 24 of some suitable construction secured to the adjacent side wall of the 100 casing.

In practice, one or the other of the dogs

19 is relieved of the influence of the holding arm 21 and engaged with the adjacent ratchet wheel 9, while the other dog is held out of engagement with the ratchet wheel.

5 When it is desired to rotate the drums so that the web will unwind from one drum and wind onto the other, the cord 15 is pulled, thereby swinging the yokes against the action of the spring 17 and in this movement 10 of the yokes the dog in engagement with the ratchet wheel rotates the latter to wind the web upon the drum connected to such ratchet wheel. Upon the release of the pull cord, the springs 17 react and restore the yokes to normal position, so that the above operation 15 may be again repeated. In the return of the yokes to normal position under the action of the springs 17, the stems of the yokes engage the buffers 24, thereby limiting the 20 movement of the yokes under the action of the springs. In each movement of the drums, the name of one station is moved out of the sight opening and the name of the next station moved into the sight opening, 25 and when the car has traversed the route in one direction and is about to travel in the opposite direction the positions of the dogs may be reversed so that the web will be rewound upon the previously unwinding drum.

30 Surrounding the opposite end of each shaft 4, 5 is a collar 25 formed, at diametrically opposite points, with outwardly projecting arms 26. One arm 26 is fastened to the casing as at 27, while the other arm is 35 formed with a longitudinal bore 28 opening into the collar and slidably mounted in the bore 28 is a shoe 29 normally held in frictional engagement with the adjacent portion of the shaft by means of a spring 30 and 40 threaded into the outer end of the bore 28 is a plug 31 acting to hold the spring within the bore. This shoe 29 and the spring 30 constitute a brake or check that acts to hold the shaft against accidental rotary movement.

45 I claim:

1. In a street or station indicator, a casing having a sight opening therein, shafts journaled in said casing above and below 50 said sight opening respectively, drums fixed

upon said shafts, a web having the names of the stations thereon and having the ends thereof secured to said drums and wrapped about the same and the intermediate portion movable across said sight opening, ratchet 55 wheels on the ends of said shafts respectively, yokes loosely mounted upon said shafts and having stems projecting toward each other and overlapping and formed with elongated slots, spring dogs pivoted within 60 said yokes and adapted to engage said ratchet wheels, a pin passed through said slots, a yoke connected to said pin, a pull cord connected to said last-yoke whereby the first-mentioned yokes may be swung to rotate said ratchet wheels, and means carried by each yoke for holding the dog thereon out of engagement with the ratchet wheel.

2. In a street or station indicator, a casing having a sight opening therein, shafts journaled in said casing above and below said sight opening respectively, drums fixed upon said shafts, a web having the names of the stations thereon and having the ends thereof secured to said drums and wrapped about 70 the same and the intermediate portion movable across said sight opening, ratchet wheels on the ends of said shafts respectively, yokes loosely mounted upon said shafts and having stems projecting toward each other and 75 overlapping and formed with elongated slots, spring dogs pivoted within said yokes and adapted to engage said ratchet wheels, a pin passed through said slots, a yoke connected to said pin, a pull cord connected to 80 said last-yoke whereby the first-mentioned yokes may be swung to rotate said ratchet wheels, means carried by each yoke for holding the dog thereon out of engagement with the ratchet wheel, and a horizontal guide 85 carried by the casing and receiving one end of said pin to guide the latter in its movement under the action of said pull cord.

In testimony whereof I affix my signature in presence of two witnesses.

MICHAEL FITZGERALD.

Witnesses:

JAMES H. CONLEY,
GEORGE R. CONLEY.
